FLIGHT INSTRUMENT TRAINING HOOD FOR PILOTS

Frederick E. Urben, Englewood, Colo., assignor to
Jeppesen and Company, Denver, Colo., a corpora-
tion of Colorado

Filed July 18, 1966, Ser. No. 3,248

Term of patent 14 years

(Cl. D2—232)

FIGURES 1 and 2 are perspective views of a flight instrument training hood for pilots showing my new design;

FIGURE 3 is a top plan view thereof;

FIGURE 4 is a side elevational view thereof;

FIGURE 5 is a bottom view thereof;

FIGURE 6 is a front elevational view thereof; and

FIGURE 7 is a rear elevational view thereof.

I claim:

The ornamental design for a flight instrument training hood for pilots, as shown.
